Primary Examiner — Sandra Snapp*Assistant Examiner* — Jasmine L. Comedy(57) **CLAIM**

The ornamental design for an underwater building material as shown and described.

DESCRIPTION

1. Underwater building material

1.1 : Front

1.2 : Back

1.3 : Perspective

1.4 : Right

1.5 : Left

1.6 : Top

1.7 : Bottom

1.8 : Exploded

The broken lines shown in FIGS 1.3, 1.7 and 1.8 corresponding to the top and bottom portion and 1.6 corresponding to the inside structure depicts portions of the underwater building material that forms no part of the claimed design.

1 Claim, 8 Drawing Sheets(56)
